(57) **CLAIM**

The ornamental design for a “fishing line connector,” as shown and described.

DESCRIPTION

FIG. 1 is a perspective view of a fishing line connector showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a first reference view showing the claimed design in use.

The remaining broken lines shown in FIG. 8 depict environment and are for illustrative purposes only and form no part of the claimed design.
